UNITED STATES PATENT OFFICE.

HERMAN C. SCHLICKER, OF NEW YORK, N. Y.

KINETOGRAPH.

1,256,931.

Specification of Letters Patent. Patented Feb. 19, 1918.

Application filed April 11, 1914. Serial No. 831,147.

To all whom it may concern:

Be it known that I, HERMAN C. SCHLICKER, a citizen of Germany, and a resident of the borough of Manhattan, in the county 5 of New York and State of New York, have invented certain new and useful Improvements in Kinetographs, of which the following is a specification.

This invention pertains to an apparatus 10 for taking motion pictures, and more particularly relates to the production of a number of images of reduced size upon an endless film.

One of the objects of the invention is to 15 produce an improved apparatus of the character described that is especially adapted for use by amateurs.

A further object is to adapt the kinetographic apparatus for the ready insertion 20 and removal of a plurality of film holders, so that unexposed films may be placed therein in daylight, and others substituted after exposure, without danger of the films becoming light-struck.

25 Another object is to provide a kinetograph with a self-contained spring-motor, and appropriate connections, adapted to propel the endless film band, as well as a co-acting shutter and lens traverse, in such 30 a manner that a person can hold the apparatus in hand while in action without causing detrimental vibrations therein.

A still further object is the provision of 35 means for so positioning the images taken on the film that the same will appear correctly placed at all times and in proper sequence thereon, without wasting any of the film's sensitized surface.

Still another object is the production of 40 a motion picture camera composed of but few parts, simple to operate, and of low cost of manufacture.

Further objects will become apparent as the specification proceeds.

45 The advantages of the invention are best realized in a construction comprising a self-contained casing divided up into a suitable number of compartments, to wit: first, a compartment adapted to receive one by one, 50 independently or serially, any desired number of removable holders containing each an endless or tubular web of sensitized material constituting the film; a second compartment extending alongside the first, and in- 55 closing a main drive designed to impart

continuous motion to a shutter-operating mechanism and intermittent motion to a film-actuating device; a third compartment communicating with the first and second, and containing an objective-translating 60 mechanism connected up with the said intermittently-actuated device to move in synchronism with a section of the film intended to receive the images, the latter being taken step by step in individually offset relation 65 on the film and in helical formation; and a fourth compartment underlying the first, and wherein is located a spring-motor arranged for engagement with the main drive and to actuate the therewith connected 70 mechanisms without affecting their respective steadiness of operation during exposure of the film to the light.

It will be manifest to those skilled in the art that the invention may be embodied in 75 several different constructions, the accompanying drawings showing one of these by way of illustration.

In the said drawings:

Figure 1 is a sectional side view of a portable form of the apparatus, the section thereof running along the irregular line 1—1 of Fig. 2, looking in the direction indicated by the arrows in the latter-named view;

Fig. 2 is a sectional plan, taken from the line 2—2 of Fig. 1, looking downward, as the arrows therein indicate.

Fig. 3 is a side elevation of a locking slide, seen in edge view in the preceding figure;

Fig. 4 is a front view, looking from the left end of Fig. 1;

Fig. 5 is a fragmentary view showing the main drive in side elevation, as seen looking downward from the upper left-hand side of 95 Fig. 2; and

Fig. 6 is a fragmentary face view of a flexible film used in conjunction with the apparatus, the view illustrating diagrammatically the arrangement of the images 100 thereon, considered both individually and collectively.

In these views, the letter A represents a casing which in the present embodiment of the invention is conveniently made of rectangular form, as shown in the drawings. This form of casing includes, therefore, a top wall 10, a bottom wall 11, a front wall 12, having an elongate opening 13, a rear wall 14, provided with a door 15, and side 110

walls 16, 17. The several elements here enumerated as constituting the casing have other parts thereto attached or co-acting therewith, which will be the easier traced or 5 located by reference to the numerals just given.

Inside the casing A, as shown herein is a vertical partition 18 and a raised floor 19 meeting each other at one edge, as best seen 10 in Figs. 2 and 4, the same extending forward from the rear jamb and the sill of the door 15, respectively, for a predetermined distance within the casing, where they join and rest upon a transverse partition 20, at 15 their inner ends. See also Fig. 1. Running in the same direction as 20, are two other narrow partitions 21, 22, extending across the top and bottom walls, 10, 11 respectively; each for a distance co-extensive with the 20 width of the said floor 19, the upper and lower edges of the partition 22 being offset one from the other, as shown. These data are given merely as an example of a practicable construction, as will be understood, 25 since obviously recourse could be had to numerous other means and ways of producing the requisite divisions in the casing.

A film-holder 25 is insertible through the opening covered by the door 15, into the 30 above described casing A. In its preferred form, this holder includes parallel sides 26, 27, designed to face respectively the top wall 10 and floor 19 of the casing; curved ends 28, 29, to be located respectively opposite the 35 front opening 13 in the wall 12 and the door 15 of the wall 14; and a bottom 30, to be placed parallel with the side wall 17. These parts 27—30, form together an oblong 40 container, which is closed by a cover 31, recessed as at 32 to take over the rim of the holder 25, and adapted to render the latter light-tight. The cover 31 may be held in 45 position by spring catches, such for instance as are shown at 33, in the upper right-hand portion of Fig. 2.

Brackets 34, 35 extend from the inner face of the said cover 31, into the film-holder 25. The bracket 34 revolvably holds a hexagonal or other prismatic roller 36, which normally 50 is maintained in a relatively fixed position, and the bracket 35 affords a similar support for a cylindrical roller 37, rotatably carried in a frame 38, resiliently sustained in the latter-named bracket. A spring 39 urges 55 the frame 38 away from the bracket 35, while the outward movement of said frame is limited by heads or enlarged ends 40 of guide stems 41, these elements constituting a tensioning device for the film, presently to be 60 described. To hold the frame 38 in a retracted position, whenever required, a slide 42, having elongated apertures 43, enlarged at one end as shown in Fig. 3, is adapted to take over reduced portions 44 of the guide 65 stems 41, when the frame 38 is pressed in-

ward. This last operation becomes necessary when the film is applied to or taken off the rolls 36 and 37.

The film upon which the images are taken consists of a tubular or endless flexible web 70 50, stretched over the aforesaid prismatic and cylindric rollers 36, 37, and having marginal perforations 51, arranged to take over teeth 52, at the opposite ends of the roller 36. At such times as the roller 36 is rotated, 75 the teeth 52 thereon engage the perforations 51 in the opposite edges of the web 50, and thus the latter is positively propelled, while the straight flat faces of the roller present correspondingly-shaped sections of the web 80 outward. A gear-wheel 54, placed outside of the cover 31, is fixed to a projecting end 85 of a spindle 55, to which the roller 36 is fastened.

The curved, forward end 28 of the film-holder is formed with a transversely-elongated opening 56, which is normally, covered by a suitable closure which may be a sliding door 57 as shown, prior to the insertion of the holder into the casing. At a predetermined point inside the latter, for instance, under the floor 19, is attached a spring arm or a plurality of spring arms 58, having each a hook 59 at its free end, projected into the path of a ledge 60 on the said 95 sliding door. As the holder 25 is being inserted into the casing, the hook 59 encounters the ledge 60 in its highest position, to wit, when the opening 56 is closed. A further movement of the film-holder inward 100 causes the spring arms to yield, while at the same time the sliding door is pulled open and retained in that position by the hooks 59. To prevent light from prematurely entering the apertured end of the holder, during its introduction into the casing, the surface of the floor 19 upon which the holder slides may be suitably lined, for example with velvet, and a yielding strip 61, of felt or the like, may be applied transversely on the 110 opposite side of the holder, to effect a light-tight joint thereover. A spring 62, bearing centrally upon the same side of the holder, from the under side of the top wall 10, may be employed to keep the holder firmly in 115 position against the surface of the floor 19. The laterally-arranged springs 58 and centrally-disposed spring 62 together serve as a positioning device for the holder, while the hooks of the former enable them to perform 120 the additional function of an automatic door-opener and door stop. This constitutes a convenient construction, still it will be understood that some other type of closure, equally effective, may be substituted for the 125 sliding door 57, and that, whatever means are adopted for closing the apertured end of the film holder, the same could be operated in other ways.

The hereinbefore mentioned gear-wheel 54 130

is brought into meshing engagement with a similar gear 67, secured to a spindle 68, that is rotatably carried in a bracket 69 (Fig. 5) fastened as shown to the wall 11 of the casing. On the spindle 68 is also fixed a sprocket-wheel 70 more fully referred to hereinafter, and one member of a pair of intermittent gears, which member as exemplified herein may be a star-wheel 71 of Geneva 10 movement type. The latter, in a well-known manner, is given alternate periods of movement and rest by the other member of said paired gears, which may consist of a co-acting single-tooth or pin wheel 72. The intervals of repose of this intermittent mechanism correspond in extent to the superficial sections of the polygonal roller 36, the arrangement being such that, each time its motion is arrested, the said roller presents 15 one of its flat or straight faces to the light-rays passing through an objective placed in front thereof. Any other suitable form of mechanism capable of imparting intermittent motion to the prismatic roller would, of course, subserve the same purpose.

The impeller gear 72 is fixedly mounted on a spindle 73, which also carries a combined spur and bevel gear-wheel 74. The straight or spur teeth of the latter engage similar 20 teeth of a pinion 75, attached to one end of a rotary shutter 76, which has its trunnions journaled in bearings 77, 78, mounted oppositely on the inner surfaces of the casing's side walls 16 and 17. This shutter is preferably formed of a tube having two of its 25 opposite quadrants cut away, as seen in cross-section in Fig. 1, and its speed of rotation, which is continuous, is such that the other quadrants thereof obscure or cut off the 30 light-rays while the film travels a distance corresponding to the angular movement of the flat sides of the prismatic roller 36. The form of shutter here described is quite suitable, because of its simplicity and effectiveness, though the invention contemplates the 35 use of any other form, of whatever nature, that is adapted to the purpose stated.

Disposed in alignment with the prismatic roller 36 and the shutter 76, is the light-focusing portion of an objective slide 82, carrying the usual reduction lenses for casting an image of diminished size upon the film 50. The slide 82 is operatively maintained edgewise between parallel guides 83, 40 84. A vignette plate 85, offset to one side so as to clear the shutter 76, is carried by this slide, and translated with it by means of a screw 86, which is journaled in bearings 87, 88, projecting inwardly from the opposite 45 side walls, 16, 17. An arm 89, having a fixed jaw 90 curved over the screw 86 with a slight clearance therebetween, and a movable jaw 91 hinged to 90 as at 92, affords an operative connection between the objective slide and 50 the said screw, the hinged jaw being formed

with threads adapted for engagement with corresponding threads on the screw, when placed in the position illustrated in Fig. 1. A spring clip 93, carried by the latter-named jaw, is adapted to take over the upper edge 70 of the fixed jaw, and maintains the parts in locked position. At such times as it is desired to move the slide 82 quickly, irrespective of the screw 86, the spring clip 93, which is suitably formed so as to constitute also a 75 finger grip, is swung outwardly in order to disengage the movable lower jaw 91 from the threads of the screw. One end of the latter carries a sprocket-wheel 94, which is connected up, by a chain or link belt 95, to the 80 before-mentioned sprocket-wheel 70, on the intermittently-operated spindle or counter-shaft 68. The arrangement is such that when the screw 86 rotates, the lens or objective carrying slide 82 is translated in predetermined synchronism with the advancement of each image taken on the film 50. While this is the mechanical connection at present favored for operating the lens transverse from the main drive, nevertheless it will be 85 readily perceived that other operative connections, either direct or indirect, may be substituted for the one herein illustrated.

To shut out all light from the casing, excepting what enters into it through the objective, a flexible screen, for example an opaque curtain 96, is fastened at its middle portion to the slide 82, in such a way that it permits the inner lens holder thereof to project through, while its ends are arranged to 100 wind alternately upon spring-actuated rollers 97, 98, to which they are attached. Mounted in this manner, the curtain will be automatically wound and unwound from the opposite ends thereof, as the objective is 105 being translated in one direction or the other. The side edges of the curtain are caused to follow closely the adjoining opposite edges of the partitions 21 and 22, which coact with the curtain in precluding the 110 light, that flows in across the front opening 13, from reaching the interior of the casing and the film exposed therein, otherwise than through the objective. A single and flexible curtain is here spoken of, but it will be obvious to experts in this art, that any duplication or manifolding thereof and any structural change therein not impairing its capability to discharge the function above expressed are contemplated by the present invention.

Strips 99, of opaque material, preferably resilient are attached across the bottom 30, and lid 31, respectively so as to stand vertically against the side wall 17 and partition 18 of the casing when the holder is inserted therein. These strips it will be seen, afford an additional means of excluding light from the casing.

The spindle 73, whereon the bevel-gear 74 130

is secured and from which all motion to drive the various mechanisms originates, can be turned either by a hand-crank 100, or by means of a co-acting bevel pinion 101, fastened to one end of a divided shaft 102, which is journaled in bearings 103, projecting from the inner face of the side wall 16 of the casing. The shaft 102 carries at its other end a miter-gear 104, in mesh with a co-acting miter-gear 105, correspondingly positioned on another shaft 106. The latter also carries a bevel-pinion 107, in meshing engagement with a bevel-gear 108, rotated by a spring-motor 109. Another bevel pinion 110 meshes also with the bevel-gear 108 and is driven thereby, the latter-named pinion being fixed to one end of a shaft 111, which is journaled in bearings 112, 113, fastened to the bottom wall 11. A collar 114, fixed to the shaft 111, has attached thereto a plurality of weighted spring-arms 115, each by one end, the other ends whereof are connected with and serve to draw a collared disk 116, slideable on the opposite extremity of said shaft, and cause it to contact with a friction button 117 on said bottom wall, when the speed of the bevel-gear 108 becomes excessive.

The winding of the spring-motor can be effected with a key 118, or by the hand-crank 100 as either is most available for the purpose. Where it is deemed advisable to throw the spring motor 109 out of gear with the manually operated drive mechanism, a clutch 119 mounted on the divided shaft 102 is opened by means of a handle 120 extending outside of the casing. It is likewise optional to use the forms of gearing shown between the spring-motor and the main drive, and again between the motor and its speed-governor, or to resort to other means of transmitting and regulating the motion, as may be preferred.

In the operation of the apparatus, the film-holder 25 is first charged. This is done preferably in a dark room, by removing the lid or cover 31, causing the rolls 36 and 37 thereon to approach each other, slipping the endless film belt 50 over said rolls while thus approached, and then releasing the yieldable frame 38 so as to place a sufficient tension on the film to offset any variation in the length thereof, care being taken that the marginal perforations 51 properly engage the teeth 52 on the prismatic roller. Next, the film, held firmly in place from the under side of the lid, is inserted into the body of the holder, and the lid itself is applied to the rim of the latter, the spring catches 33 serving to keep the various parts securely bound together. The operator may carry several holders, each charged in the manner just described and the same will be inserted by him through the door 15 into the compartment reserved therefor within the cas-

ing A, one at a time. In so doing, the sliding door 57 at the forward end of the holder is brought into contact with the spring arms 58 and is opened thereby, so that when the inserted holder has been located in correct position, and the gear-wheels 54 and 67 engage each other, the vignette plate 85 stands closely facing the foremost flat section of film thereto presented by the prismatic roller 36. The vignette permits the casting of images on the film, of such sizes only as are equal to the advance thereof, as produced by the angular movement of the prismatic driving roller, rotated by any desirable means,—*i. e.*, whether by the hand-crank 100, or the prime mover 109, or through other agencies. If the self-contained spring-motor hereinabove described be employed, the operator will be enabled to hold the entire apparatus in hand and support it directly on his own person during its operation, without danger of losing or disturbing the steadiness and regularity of motion required. During the intervals of time when the advance of the film takes place, the shutter 76 obscures the light from the objective. Simultaneously, the screw 86 propels the objective carrying slide 82 a predetermined amount, so that the next image cast over the film will be offset or side-stepped from the preceding one thereon, in such a manner that all the images will follow one another in combined helical and side-step formation around the surface of the web 50, as indicated in Fig. 6. The web's sensitized surface may thus be covered with a continuous set or series of images or pictures, adapted both individually and collectively for an ideal presentation, in their true positions, of the moving and other objects photographed. The length of the film's surface is gaged in accordance with the course of the objective slide in one direction. When the slide 82 has traveled the full length of the threaded portion of the screw 86, it is swiftly returned to its starting point after the movable jaw 91 of the arm 89 has been swung away from engagement with the screw, which enables the slide to be freely moved. Another set of pictures, which may be a serial continuation of the previous one taken, may be collected on another film, substituted for that already filled. The very act of taking out of the casing the holder containing the film covered with pictures operates to close the sliding door 57 thereof, since the ledge 60 of the latter strikes against the upper end of the partition 20 while being drawn outward, thereby shutting the said sliding door, whereupon the holder can be slightly raised above the floor 19 and removed through the hinged back door 15, to make place for the insertion of another charged with a fresh film.

It will be observed that the four compartments hereinbefore named as comprised in the casing A and severally fitted for occupancy by the principal parts of the apparatus, intercommunicate and overlap one another so as to form three L-shaped divisions, respectively designated by the reference characters B B¹, C C¹, and D D¹, in Figs. 1, 2 and 5. The first division B B¹ contains the film-holder and the driving mechanism. The second division C C¹ is occupied by the power transmitting gears and also the driving mechanism, C¹ thereof being the same as the section B¹ of the first division. The third division D D¹ incloses the motor and the power transmitting gears, its section D¹ being the same as the section C of the second division. This mode of dividing up the casing is productive of great compactness for the apparatus, and may be carried out effectively by other means than the floor and partitions herein specified, as will be apparent to persons skilled in the art to which the invention appertains.

Although described specifically as a camera or machine for taking motion pictures simply, it is quite conceivable that this improved kinetograph could be used as well for reproducing or projecting such pictures upon an external screen, only by providing a suitable lens in one wall of the casing and a light inside the film therein. All such changes are within the pale of the invention, and the right to effect the like is hereby reserved.

Having described my invention what I desire to secure by Letters Patent and claim is:—

1. A kinetograph comprising in combination an objective, mechanism for translating the same, means for supporting a film opposite said objective, a device for intermittently exposing said film before the latter, a light obscuring element protecting such film portion as should not be exposed, and a vignette interposed between the exposed part of the film and the objective and translatable with the objective.

2. A kinetograph comprising in combination a casing provided with an elongated aperture for the exposure of a film therein, an objective translatable relatively to the exposed part of the film, and means for excluding light from the portion of the aperture unoccupied by said objective.

3. A portable kinetograph comprising a casing adapted to receive an intermittently movable film, an objective arranged to travel in synchronism with the movements of said film transversely thereof, a holder for the latter having an extended opening permitting its travel therein opposite said objective, means for excluding light from the portion of the film not to be exposed through the opening, a drive mechanism, operative

connections between said drive and the movable elements, and a motor actuating said mechanism.

4. A kinetograph comprising a casing, an objective therein, a film-holder having an opening adapted to be positioned opposite said objective, a closure for said opening, and means for closing and opening said closure while the latter is inside said casing.

5. A kinetograph comprising a casing, an objective mounted therein, a removably insertible film-holder having a closure adapted to be opened opposite said objective, an element serving to open said closure while remaining in said casing, means for actuating said element, and drive mechanism to propel the film in the holder subsequently to the opening of the closure.

6. A kinetograph comprising a casing with an elongated aperture, a film-holder having an opening of proportionate length positioned opposite said aperture in said casing, an objective translatable between the aperture and said opening, a closure adapted to cover and uncover the latter interiorly of the casing, means for opening said closure to permit exposition of the film to said objective at any point of its travel, and an element movable with the objective to exclude light from the unexposed portion of the film.

7. A kinetograph comprising a casing formed with an elongated light receiving aperture, a film-holder in said casing having a commensurate opening, a closure for the latter operable interiorly of the casing, an objective guided rectilinearly between said opening and said aperture in position to register with the opening when uncovered, means for imparting a graduated translatory movement to said objective, and an element coöperating with the objective to localize the flow of light through the aperture.

8. A kinetograph comprising a casing, a translatable objective in the same, a film-holder open for the full width of the film opposite said objective, means within said holder operating to move the film therein so as to expose a portion of its width periodically within the holder's opening, and means for excluding light from said opening beyond the exposed portion of the film.

9. A kinetograph comprising, in combination, a holder formed with an opening to admit light-rays therethrough, said holder containing an endless film extending for its full width across said opening, means for moving the film including a rotatable element adapted to present a fractional part of the film for exposure through said opening, means for excluding the light from the holder beyond the exposed part of the film, and a traveling objective associated with said light excluding means.

10. A kinetograph comprising an apertured casing, a film holder therein arranged to receive light through the aperture thereof, a flexible endless tubular film in said holder, and rollers engaging opposite portions of said film, one roller operating to present sections of the film toward said aperture, and one roller exerting a tension upon the film.
11. A kinetograph comprising a casing provided with a light-admitting aperture, a removable film-holder having an opening adapted to register with said aperture, the film being arranged for exposure through said opening and the holder therefor designed for free insertion in said casing, rigid means for guiding said film-holder into position, and resilient means serving to maintain the same against said rigid means.
12. A kinetograph comprising a casing having an aperture for the admission of light, a holder for an endless film, said holder having an opening to receive light from said casing, rollers engaging opposite portions of the film so as to keep it in alignment with said aperture and said opening, and means within the holder for varying the distance between said rollers.
13. A kinetograph comprising, in combination, a translatable light-focusing means, a film-holder having an opening opposite the latter, the film being movable in said holder for exposure through said opening, and a vignette projecting through said opening from the light-focusing means toward the exposed part of the film.
14. A kinetograph comprising a casing, a translatable light-focusing medium connected therewith, a removable film-holder having an opening facing said medium, the film being movable in said holder for exposure through said opening, a closure for the latter, a vignette projecting from the light-focusing medium toward the film, and means operating to open said closure, said means being actuated within the casing and permitting said vignette to enter said opening, thereby confirming the light to sections of film successively exposed.
15. A kinetograph comprising, in combination, a translatable light-focusing means, a film inclosing holder having an opening registering with said focusing means, a shutter interposed between the latter and said opening, and a vignette held from the focusing means between the exposed part of the film and said shutter.
16. A kinetograph comprising, in combination, a translatable objective, a film-holder positioned to receive light from said objective, the film being movable in said holder for exposure to the light, and a vignette carried by the objective interposed between the latter and the exposed part of the film.
17. A kinetograph comprising, in combination, a translatable objective, a holder having an elongated opening disposed in parallelism with the direction of translation thereof, said holder containing an endless film arranged to revolve with its transverse axis parallel to said opening, means for moving said objective together with the film to bring sections of the latter for exposure through said opening simultaneously with the translation of the objective, a shutter with spaced edges permitting exposure of one of said sections, means for operating said shutter in synchronism with the film to exclude light therefrom at predetermined intervals, and means for excluding from the film other light than that transmitted thereby by the objective.
18. A kinetograph comprising a casing provided with an elongated light-aperture, an objective translatable longitudinally of the latter, a film-holder having an opening opposite the line of travel of said objective, means for moving the objective and the film, a driving roller for said film disposed in axial parallelism with relation to said light aperture and to the opening in the holder, and an element coating with the objective to restrict the light passing through the aperture.
19. A kinetograph comprising a casing, an objective slidable in the aperture thereof, a film-holder having an elongated aperture provided with an opening opposite said objective, means for moving the latter and the film, and a light excluding screen behind said aperture connected with the objective so as to be operated thereby.
20. A kinetograph comprising a casing provided with an elongated aperture, an objective slide translatable across said aperture, a film-holder having an opening opposite the latter, means for moving said slide and the film, a screen translatable with said slide adapted to exclude light from the portions of the aperture unoccupied by the objective, and take-up mechanism compensating the travel of said screen.
21. A kinetograph comprising an elongated casing provided with a light-aperture, an objective slide translatable longitudinally of said aperture, retaining means projecting from the casing in the line of movement of said slide, a screen surrounding the objective and translatable therewith adjacent said means, a film-holder having an opening parallel to the light-aperture, and means for moving the slide and the film so as to expose sections of the film to the objective successively through said opening.
22. A kinetograph comprising a casing provided with an elongated light-aperture extending transversely across the same, an objective slide opposite said aperture, guides for said slide, a film-holder having an opening parallel to the line of movement of the objective, means for intermittently moving

- the film in said holder for exposure through said opening, means for screening the film from the light between exposures, and translating mechanism operatively connected up 5 with the objective slide to move it step by step in one direction, said mechanism being disconnectible from the slide to permit independent return thereof in the reverse direction.
- 10 23. A kinetograph comprising, in combination, a light-focusing medium, a film-holder having an elongated opening within range thereof, means for moving the film intermittently in said holder for successive 15 exposures through said opening, means for precluding the light from passing through and by the sides of said medium while the film is in movement and for confining the admission of light to the medium when the 20 film is stationary, and mechanism operating to translate the light focusing medium in graduated amounts between exposures and to arrest it coincidently with the film, thereby causing periodical intervals of rest 25 and permitting the taking of pictures in offset relation, side-stepped individually, and following one another collectively in helical formation.
24. A kinetograph comprising a casing, a 30 film-holder removably insertible into the same, the film being completely inclosed in said holder, a support for the latter within said casing, a drive mechanism, operative connections extending from the film 35 through the holder for automatic engagement with said mechanism, and means operating to maintain the point of engagement of the mechanism with said connections at a constant distance relatively to said support.
25. A kinetograph comprising a casing, a drive mechanism mounted therein, a movable shutter connected for operation by said drive mechanism, a removably insertible 45 film-holder; an objective carrying a vignette arranged to enter into said holder, and automatically connected gearing positioned to permit the entry of said vignette into the film-holder and operating to move the film 50 intermittently from said drive.
26. A kinetograph comprising a casing, a driving mechanism mounted therein, a translatable objective slide, means for moving said slide geared for intermittent movement with said mechanism, a removably insertible film-holder having an elongated opening opposite the objective, the film being movable in said holder, and automatically engaging connections transmitting intermittent movement from said mechanism 55 also to said film.
27. A kinetograph comprising a casing, a driving mechanism mounted therein, a translatable objective slide, a screen 60 rounding the objective and secured to its said slide so as to be translated therewith, a removably inserted film-holder having an elongated opening positioned opposite said screen and objective, permanently connected gearing transmitting intermittent movement 70 from said mechanism to the slide and screen, and automatically applied and detachable connections adapted to transmit similar movement to the film from the same mechanism. 75
28. A kinetograph comprising a casing, a motor of attenuated axial dimension mounted therein, a removably insertible holder for an endless film arranged to follow an elongated course at right angles to the axial dimension of said motor, means for moving the film in said holder, and operative connections between the motor and said moving means disposed to one side of the last named elements and the film-holder. 80
29. A kinetograph comprising, in combination, a drive mechanism, a member intermittently rotated by said drive, a film-holder having an elongated aperture, an objective adapted to travel opposite said aperture, 90 means carried by said objective serving to confine the light to a certain portion of the film, a roller timed with said intermittently rotated member for propelling the film, and operative connections between the 95 drive and said member and from the latter to said roller and said objective.
30. A kinetograph comprising a casing having a plurality of compartments, a film-holder removably insertible in one of the 100 compartments thereof, an actuating roller for the film in said holder, an objective located cross-wise of the holder opposite the film, a motor of relatively short axial measurement disposed in another one of said 105 compartments with its axis extending in a plane transverse to the film-holder, mechanism including a counter-shaft arranged laterally of said motor and said holder in position to transmit motion therefrom to said 110 roller and said objective, and an operative connection between the actuating roller and said mechanism.
31. A kinetograph comprising, in combination, a casing, a drive mechanism therein, 115 an element intermittently rotated by said mechanism, a single compartment holder provided with a transversely extending aperture and containing an endless film, a light-forming medium translatable in front of 120 said aperture, means adapted to present the film in flat sections opposite the latter, other means for shielding the film from the light that might pass by the side of said medium, a connection operatively coupling the film 125 with said element, a closure for the holder's aperture operable interiorly of said casing, and means for moving the medium synchronously with the advancement of the film. 130

32. A kinetograph comprising, in combination, a drive mechanism, a motion transmitting part, a spindle intermittently operated from the latter, a single compartment holder for an endless film, said holder having an elongated opening, a closure for the latter, means adapted to present the film in flat sections for exposure opposite said opening when uncovered, an operative connection between the film-presenting means and said part, other means for focusing an image on the film, a device translating said focusing means in synchronism with the advance of the film after each exposure, and a light shielding element arranged to protect such portion of the film as should not be exposed.
- 10 33. A kinetograph comprising a casing, a light-focusing medium therein, a removably insertible film-holder provided with an opening to be positioned opposite said medium, a door for said opening, and a door opener in the casing located in the path of the holder so as to open said door during 25 insertion.

34. A kinetograph comprising a casing, light-focusing means therein, a removably insertible film-holder having an opening to be positioned opposite said light-focusing means, a door for said opening, and a combined door opener and stop adapted to engage said door upon insertion of said holder into the casing.

35. A kinetograph comprising a casing, means for focusing the light therein, a removably insertible film-holder having an opening positioned opposite said light-focusing means, a support for said holder, a door for closing said opening when removing the holder from the casing, and means operating to close said door by contacting with said support.

Signed at the borough of Manhattan in the county of New York and State of New York this 9th day of April A. D. 1914.

HERMAN C. SCHLICKER.
